UNITED STATES PATENT OFFICE.

CALVIN W. BAGBY, OF OREGON CITY, OREGON.

RAILWAY-TRACK CONSTRUCTION.

1,195,898.

Specification of Letters Patent. Patented Aug. 22, 1916.

Application filed March 25, 1916. Serial No. 86,623.

To all whom it may concern:

Be it known that I, CALVIN W. BAGBY, a citizen of the United States, residing at Oregon City, in the county of Clackamas, 5 and State of Oregon, have invented new and useful Improvements in Railway-Track Constructions, of which the following is a specification.

This invention relates to improvements in 10 railway track construction and has particular application to a track crossing structure.

In carrying out the present invention, it is my purpose to provide a railway track crossing for use at the intersection of two 15 lines of trackway, which will be constructed in such manner that the lines of rails of each trackway, at the crossing, may be made continuous or unbroken so as to prevent jarring of the cars passing over the crossing and 20 wherein the lines of rails of one trackway may be opened up and the lines of rails of the other trackway closed simultaneously so as to enable a car on the last-mentioned trackway to cross the other track and to present 25 continuous traction surfaces to such car.

It is also my purpose to provide apparatus of the class described which may be operated quickly and conveniently by the person 30 in charge of the crossing and wherein the component parts will be so arranged and correlated as to reduce the possibility of derangement to a minimum and enable access to be readily had to such parts in the event 35 of the latter becoming broken or in need of cleaning.

With the above and other objects in view, the invention consists in the construction, combination and arrangement of parts here- 40 inafter set forth in and falling within the scope of the claims.

In the accompanying drawings, Figure 1 is a top plan view of a track crossing constructed in accordance with my present in- 45 vention, the parts being shown in one position. Fig. 2 is a similar view showing the parts in the other position. Fig. 3 is a sectional view through the crossing. Fig. 4 is a similar view taken at right angles to 50 Fig. 3. Figs. 5 and 6 are detail views of the rail section.

Referring now to the drawings in detail, 1, 1 designate the lines of rails of one track- 55 way, while 2, 2 indicate the lines of rails of another trackway intersecting the lines of rails 1, 1. The portions of the lines of rails

1 immediately adjacent to the lines of rails 2 and between such lines of rails are bowed outwardly as at 3, while the portions of the lines of rails 2 between the lines of rails 1 60 are offset outwardly from the portions of the rails 2 at the opposite sides of the rails 1, as clearly illustrated in Figs. 1 and 2 of the drawings. Fixed to the inner surfaces of the respective portions of the lines of rails 1 between the lines of rails 2 are rail sections 4, while lying in face to face contact with the inner surfaces of the bowed portions of the lines of rails 1 at opposite sides of the crossing are point sections 5 respectively having the point ends disposed adjacent to the outer ends of the bowed portions and the butt ends terminating in juxtaposition to the ends of the rail sections 4. The point rails 5 form continuations of the 75 straight portions of the rails 1 at the bowed portions of such rails and these point rails are capable of sliding movement and in one position thereof the butt ends lie flush with the inner surfaces of the lines of rails 2 and 80 are spaced apart from the adjacent ends of the rail sections 4 so as to open up the trackway 2 in order that cars on such trackway may pass the crossing. In the other position of the point rails 5, the butt ends thereof 85 engage the ends of the rail sections 4 so as to close the trackway 2 and form continuous traction surfaces over the crossing for cars on the rails 1. Placed in face to face contact with the inner surfaces of the outwardly offset portions of the lines of rails 2 are rail sections 6 each divided into sub- 90 sections 7 having the inner end portions thereof rabbeted as at 8 and overlapping each other and the upper edges of the sub- 95 sections 7 at the overlapping rabbeted portions thereof are preferably crowned as at 9. The sub-sections 7 of each rail section 6 are capable of inward and outward sliding movement relatively to each other and when 100 the sub-sections are moved inwardly, the outer ends thereof are spaced apart from the point sections 5 and lie flush with the offset portions of the lines of rails 2, while when the sub-sections are moved outwardly the 105 outer ends thereof abut the point rails 5 and act to form an uninterrupted traction surface for cars passing the crossing on the lines of rails 2. These rail sections 6 are disposed in alinement with the main portions of the lines of rails 2 and form, in effect, continuations thereof so that the cars 110

may pass over the crossing. The crowned edges 9 of the sub-sections of the rail sections 6 enable the trucks of the cars to pass the crossing without jarring or rattling, 5 thereby compensating for the breaks in the rail sections 6 due to the spreading of the sub-sections to close the crossing for cars on the lines of rails 2.

The point sections 5 and the sub-sections 10 of the rail sections 6 are secured to the respective portions of the lines of rails 1 and 2 in such manner as to hold the point sections and the sub-sections in face to face contact with the respective portions of the 15 lines of rails and at the same time permit sliding movement of such point sections and sub-sections.

When the butt ends of the point sections 5 are in engagement with the corresponding 20 ends of the rail sections 4 the sub-sections 7 of the rail sections 6 are adapted to be disposed in their innermost positions so that cars traversing the lines of rails 1 may pass over the crossing without shock or jar, while 25 when the butt ends of the point sections 5 are spaced apart from the juxtaposed ends of the rail sections 4, the sub-sections 7 of the rail sections 6 are adapted to be moved outwardly so as to form continuous 30 traction surfaces for cars traversing the lines of rails 2.

In order that the point rails 5 may be moved to open position and the sub-sections 35 of the rail sections 6 moved to closed position simultaneously, and conversely, the point sections 5 move to closed position and the sub-sections 7 to open position, the following mechanism is employed: Extending transversely of the lines of rails 2 is a cross 40 bar 9' having the opposite ends thereof secured to corresponding sub-sections 7, while disposed in a plane below that of the bar 9 and arranged transversely of the lines of rails 2 is another cross bar 10 having the 45 opposite ends thereof fastened to the remaining sub-sections 7. Extending longitudinally of the lines of rails 2 and between such rails is an operating bar 11 having one end secured to the cross bar 9' and the opposite 50 end connected through the medium of a link 12 with one leg of a bell crank lever 13 fulcrumed between the lines of rails 2, while disposed below the bar 11 and extending longitudinally of the lines of rails 2 is an 55 operating bar 14 having one end connected to the cross bar 10 and the remaining end connected through the medium of a link 15 with one leg of a bell crank lever 16. The other leg of the bell crank lever 16 is 60 connected to the remaining leg of the bell crank lever 13 by means of a link 17 and also pivotally connected to the outer end of the link 15 is one end of a link 18. The other end of the link 18 is pivotally secured to one leg of a bell crank lever 19

and the other leg of the lever 19 is connected with one end of an operating rod 20 under the control of the person in charge of the crossing. Secured to the bar 11 and projecting upwardly therefrom is a pin 21 and 70 fulcrumed upon a plate 22 extending transversely of the lines of rails 2, 2 are bell crank levers 23 and 24 disposed at the opposite sides of the bars 11 and 14. The corresponding legs of the bell crank levers 23 75 and 24 are interconnected by means of a link 25 lying upon the operating bar 11 and formed with a cross slot 26 that receives the pin 21. The remaining leg of the bell crank lever 23 is connected through the medium of 80 a link 27 with one end of a rod 28 projecting through alining slots formed in the overlapping ends of the sub-sections 7 of the rail sections 6 upon one side of the trackway formed of the lines of rails 2 and 85 through an opening formed in the adjacent portion of one line of rails 2, while the remaining leg of the bell crank lever 24 is connected through the medium of a link 29 with one end of a rod 30 projecting through 90 alining slots formed in the overlapping ends of the sub-sections of the other rail sections 6 and through an opening in the adjacent portion of the other line of rails 2. The outer ends of the rods 28 and 30 respectively are connected with cross bars 31 arranged transversely of the lines of rails 1 and having the opposite ends thereof connected to the corresponding point sections 5. In the present instance, the corresponding point sections 5 at each side of the point of intersection of the trackways are also 100 interconnected by means of a cross bar 32 and the cross bar 32 is connected by means of braces 33 with the cross bar 31 and with 105 the rod 28 or 30. In the present instance, guard rail sections 34 are disposed at the point of intersection of the trackways between the lines of rails 2 and spaced apart from such lines of rails, while guard rails 110 35 are disposed parallel with the lines of rails 1 between the latter and the ends of the guard rail sections 34 are connected to corresponding ends of the guard rails 35, while the guard rails 34 are formed with 115 slots and openings to accommodate the cross bars 9 and 10 and the rods 28 and 30, as clearly illustrated in Figs. 3 and 4 of the drawings. Underlying the bases of the rails at the points of intersection thereof are plates 36 which, in the present instance, are parallel with the lines of rails 2 and to these plates 36 are fastened the ends of the supporting plate 22. At the points of intersection of the rails, the latter are suitably 120 connected together by means of angular brace arms 37 and bolts 38, while guard rails 39 are arranged at appropriate places upon each trackway to protect the wheels 125 of the trucks approaching the crossing. 130

In practice, when the rod 20 is moved in one direction, the bell crank lever 19 is swung from the position shown in Fig. 1 to the position shown in Fig. 2 and in this 5 movement of the bell crank lever 19, the operating bar 14 is actuated to draw the sub-sections 7 connected thereto inwardly, while the bell crank lever 16, the link 17 and the bell crank lever 18 slides the operating bar 10 11 in the opposite direction to move the sub-sections 7 connected thereto inwardly. Simultaneously with the movement of the operating bar 11, motion is transmitted to the bell crank levers 23 and 24 with the effect 15 to pull the rods 28 and 30 inwardly toward the center of the crossing and in this movement of the rods 28 and 30 motion is transmitted to the point sections 5 to move the latter to closed position, thereby closing the 20 track formed of the lines of rails 2 and opening the trackway formed of the lines of rails 1 so that traffic over the lines of rails 1 may pass the crossing without shock or jar. When the direction of the rod 20 is 25 reversed, the sub-sections are moved outwardly, while the point sections 5 are actuated to open the trackway formed of the lines of rails 1 and in this position of the sub-sections and the point sections, traffic 30 may pass the crossing over the lines of rails 2 without subjecting the cars to shock or jar.

While I have herein shown and described the preferred forms of my invention by way of illustration, I wish it to be understood 35 that I do not limit or confine myself to the precise details of construction herein described and delineated, as modification and variation may be made within the scope of the claims and without departing from the 40 spirit of the invention.

I claim:

1. In a railway track crossing, the combination with the lines of rails of one trackway and the lines of rails of the intersecting 45 trackway, of sections lying in face to face contact with the inner surfaces of the lines of rails of one trackway at the opposite sides of the intersecting trackway and capable of sliding movement to close the breaks in the

rails, and rail sections slidably mounted upon 50 the inner surfaces of the lines of rails of the other trackway and disposed between the lines of rails of the intersecting trackway and capable of sliding movement to close the breaks in the corresponding trackway. 55

2. In a railway track crossing, the combination with the lines of rails of one trackway and the lines of rails of the intersecting trackway, of sections lying in face to face contact with the inner surfaces of the 60 lines of rails of one trackway at the opposite sides of the intersecting trackway and capable of sliding movement to close the breaks in the rails, rail sections slidably mounted upon the inner surfaces of the lines 65 of rails of the other trackway and disposed between the lines of rails of the intersecting trackway and capable of sliding movement to close the breaks in the corresponding trackway, and means for sliding said rail sections in relatively opposite directions simultaneously whereby the breaks in one trackway may be closed and the breaks in the other trackway opened and vice versa. 70

3. In a railway track crossing, the combination with the lines of rails of one trackway and the lines of rails of the intersecting trackway, of sections lying in face to face contact with the inner surfaces of the lines 75 of rails of one trackway at the opposite sides 80 of the intersecting trackway and capable of sliding movement to close the breaks in the rails, and rail sections slidably mounted upon the inner surfaces of the lines of rails 85 of the other trackway and disposed between the lines of rails of the intersecting trackway and capable of sliding movement to close the breaks in the corresponding trackway, said last-mentioned rail sections being formed of sub-sections having the inner ends 90 thereof overlapping and capable of movement in relatively opposite directions.

In testimony whereof I affix my signature in presence of two witnesses.

CALVIN W. BAGBY.
